UNITED STATES PATENT OFFICE.

NICHOLAS BURNS, OF DETROIT, MICHIGAN.

CLOTHES PRESS OR CABINET.

No. 888,463.

Specification of Letters Patent.

Patented May 26, 1908.

Application filed August 14, 1907. Serial No. 388,444.

To all whom it may concern:

Be it known that I, NICHOLAS BURNS, citizen of the United States, residing at Detroit, county of Wayne, State of Michigan, have 5 invented a certain new and useful Improvement in Clothes Presses or Cabinets, and declare the following to be a full, clear, and exact description of the same, such as will enable others skilled in the art to which it 10 pertains to make and use the same, reference being had to the accompanying drawings, which form a part of this specification.

My invention relates to an improvement in clothes press or cabinets shown in the 15 accompanying drawings and more particularly pointed out in the following specification and claims.

In the drawings:—Figure 1 is a perspective view of the cabinet showing one of the compartments open. Fig. 2 is a vertical cross-sectional view on line $x-x$ of Fig. 1. Fig. 3 is a vertical cross-sectional view on line $y-y$ of Fig. 1.

The object of my invention is to provide a 25 clothes press or cabinet that will fully protect the wearing apparel housed within from dust due to exposure; the construction and arrangement of the parts being such that any article of dress may be readily secured without disturbing other garments hung within 30 the cabinet. Compartments are also provided for shoes, shirts, hats, toilet articles and bed clothing.

One feature of the construction is the convenient arrangement provided for articles 35 used in shaving;—provision being made for supporting the shaving outfit adjacent to a pier mirror set in the main door of the cabinet, that the person using these articles may 40 employ the mirror while shaving.

Other advantages will hereafter appear.

Referring to the letters of reference shown in the drawings: A represents the cabinet having two divisions A' and A'' , being divided 45 by a partition A^3 running from front to rear and from top to bottom of the cabinet.

B is a door hinged to the partition A^3 and in which is set a pier mirror B'.

Within the cabinet, and supported by the 50 partition A^3 and the end wall of the cabinet, is a clothes pole C designed to support suitable clothes hangers hung thereon.

D is a compartment located within the division A' designed for the reception of articles 55 used in shaving, there being a wall across the

top of the compartment, as indicated in dotted lines in Fig. 2 at d , in order that when clothing is hung within the cabinet it will not disarrange articles in the compartment D.

D' is a door hinged at its lower edge to the 60 wall of the cabinet to close the opening into the compartment D, and d' is a chain to limit the movement of the door, the object being to cause the door to serve as a shelf for razors, shaving cup, or other toilet articles when in 65 use.

E is a drawer intended for storing shoes or other articles, the opening being decked over within the cabinet as indicated at e to protect the contents of the drawer from being disarranged due to the storing or withdrawal of clothing hung within the cabinet.

F is a closet in the division A^2 and is intended for use in storing bed linen or other similar articles.

G is a drawer designed for shirts and H is a compartment in which to store hats or like articles.

It will be seen that by the use of my invention all the articles necessary to a complete 80 wardrobe may be fully protected from dust and dirt, are readily accessible and that the necessary toilet articles are so disposed of as to be within easy reach when the mirror is employed.

Having thus described my invention, what I claim is:—

In a structure of the character described, a casing comprising a top, bottom, end walls, and spaced rear and front walls and also having 90 a partition connecting the front and rear walls and also connecting the top and bottom of the structure, the front wall having an opening, a closure for said front wall opening, said closure having a mirror, a receptacle 95 upon one side of said partition near said front wall opening and having its inner end spaced from said rear wall and also having a single opening which is made through the front wall, a closure to said receptacle swinging from its lower edge, flexible elements connected to said swinging closure to limit its downward movement whereby the swinging closure forms a shelf extending from the bottom of the receptacle, a drawer upon the 100 same side of said partition upon which said receptacle is disposed, said drawer being disposed at the bottom of the structure, a platform over said drawer, a second drawer disposed upon the opposite side of said parti- 110

tion and extending from the latter to the corresponding end of the structure, a compartment above said second drawer between the latter and the top of the structure, a closure for said compartment, a cabinet beneath the second drawer, a closure for the cabinet, and a garment suspending pole arranged in the rear of the aforesaid receptacle and supported by said partition and the corresponding

end of the structure, as and for the purposes 10 set forth.

In testimony whereof, I sign this specification in the presence of two witnesses.

NICHOLAS BURNS.
